HAMMER AND WEAR-PLATE STRUCTURE
FOR ATTRITION PULVERIZERSWayne C. Rogers, Worcester, Mass., assignor to
Riley Stoker Corporation, Worcester, Mass., a
corporation of Massachusetts

Application July 21, 1950, Serial No. 175,241

10 Claims. (Cl. 241—191)

1

This invention relates to pulverizing apparatus, and more particularly to the construction of the rotor and the various parts thereof in machines of the rotary beater type.

One machine of this type which has proven to be highly successful comprises a rotatable disk mounted within a stationary casing. The material to be pulverized, for example coal, is carried through the casing by means of an air current, and pulverization is brought about by the action of interfitting stationary and revolvable impact elements mounted on the casing wall and the rotor disk respectively. In the best construction heretofore known, the rotor disk is protected from abrasion by means of a series of segmental castings bolted to the disk to provide wear plates having integral projections forming impact elements or pegs. The revolvable pegs are subjected to considerable abrasive action, as well as to the impact of the coal and of any foreign bodies which may be mingled therewith. Consequently these pegs may become worn rather rapidly, and under some circumstances they may even be broken in service. Replacement of the revolvable pegs of course necessitates replacement of the wear plates which are integral therewith.

It is accordingly one object of the invention to provide a novel construction for the rotor of a pulverizing apparatus of the rotary beater type, which will have a far longer life of useful service than prior arrangements.

It is a further object of the invention to provide a revolvable pulverizing element which is adapted to withstand abrasive action and impact without appreciable wear or damage throughout an extremely long period of operation.

It is a further object of the invention to provide a revolvable pulverizing element which can be manufactured at a cost that is low in comparison with the length of service obtainable therefrom.

It is a further object of the invention to provide a novel rotor wear plate of segmental construction which is adapted not only to protect a rotor disk but also to clamp a pulverizing element in place on such disk.

With these and other objects in view, as will be apparent to those skilled in the art, the invention resides in the combination of parts set forth in the specification and covered by the claims appended hereto.

In accordance with the invention, there is provided a revolvable pulverizing element of generally L-shaped construction having one leg forming a base for engagement with the side of a rotor

disk and another leg arranged to project from the disk in an approximately radial plane. The projecting leg is at the front of the base and it has a flat front surface to which there is secured a protective lining or armor plate comprising one or more flat pieces of an extremely hard material, such as tungsten carbide. The base is preferably of circular shape, with a hole therethrough, and arranged to fit within a circular recess in the side of the rotor disk. The base is preferably connected to the projecting leg by two laterally spaced ribs. The pulverizing element is clamped in place on the disk by a segmental plate having an opening of suitable shape through which the projecting leg extends and a hole in line with the hole in the base. A bolt or the like extends through the two aligned holes to fasten the plate to the disk and thus clamp the base against the disk.

Referring to the drawings illustrating one embodiment of the invention and in which like reference numerals indicate like parts:

Fig. 1 is a vertical section through the upper portion of a pulverizing apparatus, the section being taken substantially as indicated by the line 1—1 in Fig. 2;

Fig. 2 is a fragmentary elevation of a pulverizer rotor, as viewed in the direction indicated by the arrow 2 in Fig. 1;

Fig. 3 is a fragmentary elevation of the rotor disk;

Fig. 4 is a fragmentary section taken on the line 4—4 of Fig. 1;

Fig. 5 is a fragmentary section taken on the line 5—5 of Fig. 1;

Fig. 6 is a perspective view of a revolvable pulverizing element, as seen from its outer end;

Fig. 7 is a perspective view of the element shown in Fig. 6, as seen from its inner end;

Fig. 8 is a perspective view of a second-effect rotor wear plate, as seen from its outer side;

Fig. 9 is a perspective view of the plate shown in Fig. 8, as seen from its inner side;

Fig. 10 is a perspective view of a first-effect rotor wear plate, as seen from its outer side; and

Fig. 11 is a perspective view of the plate shown in Fig. 10, as seen from its inner side.

In Fig. 1 there is shown a portion of a pulverizer of the general type disclosed in the prior patent to Craig No. 1,714,080, granted May 21, 1929. This machine comprises a casing 20 shaped to provide a generally cylindrical pulverizing chamber 21 within which there is mounted a vertical rotor disk 22 rotatable about a horizontal axis. This disk divides the chamber 21 into an inlet

zone or first effect 24 and an outlet zone or second effect 25 which are connected by an annular passage 26 around the outer edge of the disk. The disk carries certain pulverizing elements, which will subsequently be described. A vertical cheek plate 28 is mounted within the outlet zone 25 adjacent the wall of the casing 26 and spaced appreciably from the rotor disk. This cheek plate is provided with two concentric circular rows of openings around the axis of the disk, and within each opening there is mounted a stationary pulverizing element or peg 29 which extends toward the rotor disk. These pegs 29 may be constructed as disclosed in the same Craig patent.

The present invention is principally concerned with the construction of the pulverizer rotor, including the disk 22 and the various parts mounted thereon. As best shown in Fig. 3, the disk is provided on its outlet zone side with an outer circular row of circular recesses or counterbores 31 and with an inner circular row of circular recesses or counterbores 32. The inner recesses 32 are equal in number and in size to the outer recesses 31, and each inner recess is somewhat offset rearwardly from the corresponding outer recess. A relatively small hole 34 extends through the disk within each outer recess 31, and a similar hole 35 extends through the disk within each inner recess 32, the centers of these holes being slightly offset rearwardly from the centers of the corresponding recesses. A circular row of somewhat larger holes 36 extend through the disk intermediate the inner and outer rows of recesses, each hole 36 being located substantially on the same radius of the disk as the corresponding inner recess 32. On its inlet zone side the disk is provided with a circular row of circular recesses 38 which are axially aligned with the corresponding outer recesses 31.

The rotor disk 22 provides a support for a number of revoluble impact elements or pegs 40, one of which is shown in perspective in Figs. 6 and 7. Each of these elements comprises a generally L-shaped integral structure having one leg 41 forming a base, a second leg 42 extending at approximately right angles from the front portion of the base and having a flat front surface, and two ribs 44 which connect the opposite edge portions of the leg 42 to the base leg 41. The base leg 41 is of circular form to fit within a recess 31 or 32 of the rotor disk, and a hole 45 extends through this leg in a position offset slightly to the rear from the center of the base so that the hole 45 will register with a hole 34 or 35 (as the case may be) in the disk at assembly. The flat front surface of the leg 42 is protected from abrasion by means of armor plate 46 applied thereto. This armor plate comprises four flat rectangular pieces of an extremely hard material, such as tungsten carbide in either the cemented form or the cast form. The main body of the element 40 is preferably made of steel or other strong tough metal, and the armor plate may be secured thereto by silver soldering or brazing. It will be seen that the elements 40 are arranged in two concentric circular rows, with the armored legs 42 extending into the outlet zone 25 and interfitting with the stationary pegs 29.

On the inlet zone side of the rotor disk there is mounted a circular row of impact elements or pegs 48. Each element 48 comprises a generally L-shaped integral structure of steel or the like having one leg 49 forming a base, a second leg 50 extending at approximately right angles from

the front portion of the base and having a flat front surface, and two ribs 52 which connect the opposite edge portions of the leg 50 to the base leg 49. The base leg 49 is of circular form to fit within a recess 38 of the rotor disk, and a hole 53 extends through this leg in a position offset slightly to the rear from the center of the base, so that the hole 53 will register with a hole 34 in the disk at assembly. The flat front surface of the leg 50 is protected from abrasion by means of armor plate 54 (Fig. 4), preferably tungsten carbide, applied thereto as in the case of the elements 40. The elements 40 and 48 are of similar construction as shown, the only difference being that the legs 42 of the elements 40 are somewhat longer than the corresponding legs 50 of the elements 48. It will be noted that the legs 50 extend into the inlet zone 24.

In order to hold the impact elements 40 and 48 firmly in place on the disk 22, and to protect the disk as well as the base portions of the impact elements from abrasion, there are provided two circular rows of rotor wear plates 56 and 57. The plates 56 are mounted on the outlet zone side of the disk, whereas the plates 57 are mounted on the inlet zone side of the disk. Each of these plates is shaped as a narrow circular ring sector, there being one plate 56 and one plate 57 for each of the holes 36 in the rotor disk 22.

One of the plates 56 is shown in Figs. 8 and 9. This plate is provided with a cylindrical boss 59 of the proper size to fit closely within the corresponding hole 36 in the rotor disk. The plate also has two holes 60 and 61 therethrough which register at assembly with the holes 34 and 35 respectively in the rotor disk. On the side toward the rotor disk the holes 60 and 61 are surrounded by annular ribs 63 which engage the bases 41 of the impact elements 40 at assembly. A recess 65 is provided around each hole 60 and 61 on the side away from the rotor disk. Openings 66 and 67 extend through the plate in front of the holes 60 and 61 respectively, these openings being approximately U-shaped and of such size that the legs 42 and ribs 44 of the impact elements 40 may extend therethrough at assembly.

One of the plates 57 is shown in Figs. 10 and 11. This plate is provided with a cylindrical boss 69 of the proper size to fit closely within the corresponding hole 36 in the rotor disk. The plate also has two holes 70 and 71 therethrough which register at assembly with the holes 34 and 35 respectively in the rotor disk. On the side toward the rotor disk the holes 70 and 71 are surrounded by annular ribs 73 and 74 respectively. At assembly the rib 73 will engage the base 49 of one impact element 48, while the rib 74 will engage the rotor disk. A recess 75 is provided around each hole 70 and 71 on the side away from the rotor disk. An opening 77 extends through the plate in front of the hole 70, this opening being approximately U-shaped and of such size that the leg 50 and ribs 52 of one impact element 48 may extend therethrough at assembly.

Referring now particularly to Figs. 1, 4 and 5, it will be seen that with the various parts of the rotor assembled the bases 41 of the two circular rows of impact elements 40 will be located in the recesses 31 and 32 of the disk 22, while the bases 49 of the single circular row of impact elements 48 will be located in the recesses 38. An outer row of bolts 80 will extend through the groups of aligned holes 70, 53, 34, 45, and 60, and as these bolts are tightened the plates 56 and 57 will be clamped against the bases 41 and 49 re-

spectively to force these parts against the rotor disk. Similarly an inner row of bolts 81 will extend through the groups of aligned holes 71, 35, 45, and 61, and as these bolts are tightened the plates 56 will be clamped against the bases 41 of the inner row of impact elements 40 to force these bases against the rotor disk, while the plates 51 will be clamped directly against the rotor disk. Thus the various revolving parts will be held firmly together. The heads of the bolts will lie within the recesses 15, whereas the nuts at the other ends of the bolts will lie within the recesses 65.

In the operation of the invention the material to be pulverized will be carried successively through the inlet zone 24, the annular passage 26, and the outlet zone 25 by a current of air. This material will be considerably broken up by the impact elements 48 and it will then be reduced to a fine powder by the cooperative action of the impact elements 40 and the stationary pegs 29. The projecting legs of the elements 40 and 48 will be protected from wear by the tungsten carbide armor 46 and 54 on their front faces. The base legs of these elements will be protected from wear by the wear plates 56 and 57, which completely cover these base legs. Consequently the impact elements will have an extremely long life of service. Since the wear plates have no parts which project into the pulverizing zones, these plates also will last for a long time before they will require replacement.

Having thus described my invention, what I claim as new and desire to secure by Letters Patent is:

1. Pulverizing apparatus comprising a generally circular disk rotatable about its axis, a series of impact elements of general L-shaped construction each having one leg forming a base in engagement with one side of the disk and another leg projecting from the front portion of the base and located in an approximately radial plane, a protective armor of extremely hard material secured to the front surface of each projecting leg, and a series of wear plates secured to the said side of the disk and clamping the base legs of the impact elements against the disk, the wear plates having openings therein through which the projecting legs of the impact elements extend.

2. Pulverizing apparatus comprising a generally circular disk rotatable about its axis, a series of impact elements of generally L-shaped construction each having one leg forming a base in engagement with one side of the disk, another leg projecting from the front portion of the base and located in an approximately radial plane, and ribs connecting the opposite edge portions of the projecting leg to the base leg, a protective armor of extremely hard material secured to the front surface of each projecting leg, and a series of wear plates secured to the said side of the disk and clamping the base legs of the impact elements against the disk, the wear plates having approximately U-shaped openings therein through which the projecting legs and ribs of the impact elements extend.

3. Pulverizing apparatus comprising a generally circular disk rotatable about its axis, a series of impact elements of generally L-shaped construction each having one leg forming a base in engagement with one side of the disk and another leg projecting from the front portion of the base and located in an approximately radial plane, a protective armor of extremely hard material

secured to the front surface of each projecting leg, each base leg having a hole therethrough, a series of wear plates overlying the base legs and provided with holes which register with the holes in the base legs, the wear plates having openings therein through which the projecting legs of the impact elements extend, and fastening means extending through the holes in the wear plates and base legs to secure the wear plates to the disk and to clamp the base legs against the disk.

4. Pulverizing apparatus as set forth in claim 3, in which the disk is provided with holes which register with the holes in the base legs and wear plates, the fastening means being in the form of bolts extending through the registering holes.

5. Pulverizing apparatus as set forth in claim 3, in which the disk is provided with recesses within which the base legs of the impact elements are mounted.

6. Pulverizing apparatus as set forth in claim 3, in which the disk is provided with circular recesses, and the base legs are of circular shape and located within the said recesses.

7. As an article of manufacture, an impact element for a pulverizing apparatus comprising a generally L-shaped structure having one leg of generally circular cylindrical shape forming a base and another leg projecting from the front portion of the base parallel to the axis thereof, the base having a hole therethrough which is non-concentric therewith, ribs connecting the opposite edge portions of the projecting leg to the base leg, and a protective armor of extremely hard material secured to the front surface of the projecting leg.

8. As an article of manufacture, a wear plate for use with a hammer for the rotor disk of a pulverizing apparatus, the said plate being shaped substantially as a circular ring sector and having a hole therethrough for a fastener and an additional aperture therethrough for a projecting leg of hammer, the opening being located directly in front of the said hole and being of non-circular shape to lock the hammer against rotation.

9. As an article of manufacture, a wear plate for the rotor disk of a pulverizing apparatus, the said plate being shaped substantially as a circular ring sector and having a hole therethrough for a fastening means and an opening therethrough directly in front of the hole, the opening being shaped approximately as a U to receive the projecting leg and ribs of an impact element, the said U-shaped opening being situated in a position straddling said hole.

10. In a pulverizing apparatus having a generally circular disk rotatable about its axis, an impact element of generally L-shaped construction, a wear-plate, said impact element having one leg forming a base in engagement with one side of the disk and another leg projecting from the front portion of the base, said projecting leg having a flat face located in an approximately radial plane and having a protective armor of extremely hard material secured to said flat face, and a fastening means to clamp the base leg of the impact element between the wear-plate and the disk, the said wear-plate having an opening which is similar in cross-sectional shape to the projecting leg of the impact element and through which the said leg extends.
